Filed July 7, 1928

UNITED STATES PATENT OFFICE

WILLIAM HENRY RICHARDSON, OF PARRAS, MEXICO

DECORTICATING MACHINE

Application filed July 7, 1928, Serial No. 291,056, and in Mexico July 11, 1927.

This invention relates to machines for decorticating fibrous leaves, and has for its object to provide a machine of this character capable of use in connection with the leaves of different varieties of plants, which will effectively remove the fibers and deliver them in a clean condition.

In the accompanying drawing wherein an approved embodiment of the invention is 10 illustrated

Fig. 1 is a diagrammatic view of the machine.

Fig. 2 is a perspective view of one of the rotary scraping elements removed.

15 With reference to the drawing: *a* indicates three upper metallic cylinders, *b* three lower metallic cylinders, the arrows 5 indicating the direction in which each rotates; *c* is a rubber cylinder of smaller diameter than the metallic cylinders; *d* are upper scrapers or knives of substantially triangular section, but which can also have more than three angles. These scrapers have longitudinal blades defining longitudinal grooves or hollows and rotate 20 in opposite directions as indicated by the arrows 6. *e* are lower scrapers or knives of the same form as the upper ones, and rotating also in opposite directions as at 6. Besides, the first upper and the first lower scraper rotate in opposite directions and so do the second upper and the second lower scrapers; *f* are two cleaners which do not rotate but allow the leaves to pass between them; *g* are two cylinders of such material as rubber so 25 as to grip the fibers as they come out from between the last pair of scrapers and for delivering them to the two cylinders *h*, from between which the fibers come out entirely free from pulp and juice.

30 The upper scrapers are caused to exert pressure upon the lower ones and the leaves between them, by means of springs 7 and screws 8. The pressure is thus variable. The operation of the machine is as follows:

35 By any known feeding means the leaves are introduced between the first lower and upper metallic cylinders *a* and *b*, and from there they are successively passed on to and between the following pairs of upper and lower metallic cylinders *a* and *b*, whereby they are

prepared, by the flattening action of said cylinders, to enter between the first pair of angular scrapers *d* and *e*, which as stated in the foregoing, are provided with a plurality of blades. The first pair of scrapers consists of 35 an upper scraper and a lower scraper. The axes of the several cylinders *a* and *b* are staggered while the cylinder *c* is of smaller diameter and is positioned more nearly in vertical line with the last cylinder *b* so as to aid in 40 introducing the fibers between this first pair of scrapers. The scrapers rotate with a speed from 7 to 20 times the speed of the metallic cylinders *a* and *b*, according to the nature 45 of the leaves to be treated.

50 The upper scrapers are capable of moving vertically under the tension of the springs 7, and the lower scrapers are placed in their bearings in such a manner that a mechanical oscillator, as, for instance, a cam 10, Fig. 2, 55 may give a horizontal longitudinal movement to said scrapers. This movement given to the lower scrapers has for its object to spread the fibers laterally, reducing the thickness of 60 the material to only one layer, as otherwise 65 the cleaning of the leaves would not be uniform. From the first pair of scrapers the fibers enter the second pair, which in this moment are open in order to let the fibers pass, and from there they pass between the 70 cleaners *f* which are also open in this moment, and from there they enter between the rubber cylinders *g*. The second pair of scrapers and the cleaners do not function until 75 the fibers have been grasped by the cylinders 80 *g*. When this happens, the second pair of scrapers and the pair of cleaners will close, and as the scrapers of the second pair rotate 85 in opposite directions of those of the first pair, they will scrape the rest of the leaves even 90 after this has left the metallic cylinders and the rubber cylinder.

95 The cleaners *f* take off the loose pulp and the juice which they squeeze. When the fibers leave the rubber cylinders *g* they pass between the cylinders *h*, which rotate at very high speed and which leave the fibers completely clean.

Having thus described my invention what I claim is:

A decorticating machine including upper and lower sets of cylinders adapted to receive therebetween the material to be treated, the axes of the upper and lower cylinders being staggered, upper and lower rotary scrapers arranged to receive the material leaving said cylinders and each including a plurality of scraping blades, a gripping and guiding cylinder of less diameter than the first mentioned cylinders cooperating with the first mentioned cylinder disposed nearest the scrapers thereby to cause introduction of the material between said scrapers, non-rotatable cleaning elements arranged adjacent the rotary scrapers and behind the latter with respect to the direction of travel of the material, rotatable delivery elements, and rotatable gripping and feeding elements interposed between the cleaning elements and the delivery elements.

In testimony whereof I have affixed my signature.

WILLIAM HENRY RICHARDSON.
